(57) **CLAIM**

The ornamental design for a disposable diaper with camouflage pattern, as shown and described.

DESCRIPTION

The file of this patent contains at least one drawing executed in color. Copies of this patent with color drawings will be provided by the Office upon request and payment of the necessary fee.

FIG. 1 is a top view of a disposable diaper with camouflage pattern, showing my new design; and

FIG. 2 is a bottom view thereof;

FIG. 3 is a front view thereof, the back view being a mirror image thereof;

FIG. 4 is a right side view thereof, the left side being a mirror image thereof; and,

FIG. 5 is an isometric view thereof.
